UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

LINOTYPE-MACHINE.

No. 901,478.

Specification of Letters Patent. Patented Oct. 20, 1908.

Application filed March 10, 1908. Serial No. 420,130.

To all whom it may concern:

Be it known that I, JOHN R. ROGERS, of Brooklyn, county of Kings, and State of New York, have invented a new and useful Improvement in Linotype-Machines, of which the following is a specification.

My invention has reference to line-casting machines of the general organization represented in Letters Patent of the United States #436,532, in which a composed line of matrices and expansible wedge spacers or justifiers is transferred to the face of a slotted mold in which the slug or linotype is to be cast, and there justified by expansion of the spacers.

In producing tabular work, and work in which continuous cancellation lines are extended through the characters, it is found advisable to omit the use of the automatic spacers and effect the justification of the line at the composing point by the introduction of suitable spaces by hand. In order that this may be speedily done, it is necessary to provide at the composing point, means for accurately and positively limiting the length of the matrix line.

My invention relates to means for this purpose, adapted to be thrown into and out of action at will, and so constructed as not to interfere with the automatic justification when the machine is running under ordinary conditions.

I have shown my improvement in forms which are commercially used in Mergenthaler Linotype machines, and all parts of the machine other than those shown herein, may be of the construction shown in U. S. Patent #436,532, or of any other suitable construction.

In the drawings,—Figure 1 is a front elevation of the assembling mechanism with my improvements incorporated therein, portions of the front being broken away to expose other parts to view, the parts being shown in the position which they occupy during the assemblage or composition of the line. Fig. 2 is a similar view with the line-confining device, the subject of the present invention, in operative position as it appears during the justification of the line by hand.

Fig. 3 is a vertical cross-section on the line 3—3, Fig. 2. Fig. 4 is a front elevation of the assembling mechanism, with the confining devices in an alternative or modified form in the positions which they occupy

during the composition of the line. Fig. 5 is a similar view with the line-confining devices in action. Fig. 6 is a cross-section on the line 6—6, Fig. 5.

Referring to Figs. 1, 2 and 3: A represents the vertically movable assembling-elevator, having in its upper end a horizontal groove or channel into which the matrices B are delivered successively side by side to form the line, as shown.

C is an inclined traveling belt on which the matrices delivered from the magazine are carried downward one after another toward the end of the line.

D is an inclined surface to support and guide the matrices after leaving the belt, and for drawing each one to the end of the line behind the preceding matrix.

E is a vertically rotating star-wheel in front of which the matrices are delivered, and by which they are forced against the end of the line, and the line advanced bodily to the left to make room at the right for the incoming matrices.

F is a yielding resistant in the form of a horizontally sliding bar mounted in the main-frame and provided at one end with an upright finger f, which bears against and supports the matrix at the front or left end of the line. This resistant, frequently known as the assembler-slide, is urged to the right by a spring and is held, as it is advanced step by step to the left, by a friction-brake G.

The foregoing parts may all be constructed and arranged to operate in the usual manner.

In ordinary composition, in which the justification of the line is effected by automatic spacers set into the line during its composition, and thereafter expanded, it is not necessary that the matrix line shall be composed to an exact length. When, however, the lines are to be justified or spaced out to a predetermined and uniform length by the manual introduction of spaces or spacing matrices, it becomes necessary to provide means for exactly determining and limiting the length of the line during such justification, and it is to this end that the present invention is directed.

The preferred device for the purpose, shown in Figs. 1, 2 and 3, is a dog or jaw H pivoted at h to the main-frame or other fixed support and so formed that it may be turned upward out of action, as shown in

Fig. 1, in order to let the matrices descend in the usual manner to the end of the line between the star-wheel and the finger f until the mechanical composition of the line is completed, or in other words, until the line has reached such length that its completion and justification by hand are necessary. When this point is reached, the dog is turned to the position shown in Fig. 2, so that its upper end presents a vertical surface against the right end of the matrix line, thus confining the line between the end of the jaw H and the finger f . The assembler-slide is provided with a stud h^3 . When the jaw H is in the operative position, shown in Fig. 2, this stud will abut against the outer end of the jaw, as shown in Fig. 2, and limit the movement of the finger f to the left, thus positively limiting the distance between the finger f and jaw H so that it corresponds exactly with the length or measure of the line demanded.

It will be observed that the finger and the jaw serve as solid supports between and against which the composed line may be expanded or justified by the introduction of additional spaces at suitable points between the matrices in the same manner that the justification of hand-set type is carried on in a printer's "stick".

After the justification of a line is completed, it may be lifted from between the confining surfaces by the elevation of the assembler A , and transferred thence to the casting mechanism in the usual manner, the usual justifying action at the casting point being omitted.

In order to permit the introduction of the jaw H , the supporting-block D is cut away on the under side and the end of the jaw so formed that when turned upward to its operative position, its end will serve as a continuation of the surface D and to assist in guiding the matrices downward to the line.

During the justification of the line, the jaw H may be held in position by hand, but in order to lock it temporarily and to provide for its automatic release after the matrix line is transferred, I provide the lower end with a pivoted latch h' , urged outward by a spring-actuated bolt h^2 , and arranged to engage over a stud h^3 on the slide F when the jaw is turned to its operative position, as shown in Fig. 2. When the jaw H is turned to its operative position, there is commonly a slight space between its outer or rear end and the stud h^3 . This permits the slide F and finger f to move slightly to the left before they are finally arrested, this movement permitting the subsequent introduction of the hand-set spaces to justify the line. After the line is lifted from the assembling position and above the finger f , the slide F is

returned to the right as usual, and during such movement it carries the stud h^3 out of engagement with the jaw, which falls to its original or inoperative position, shown in Fig. 1, owing to the preponderance of weight at its lower end.

In operating the machine, the operator manipulates the keys and assembles the line of matrices as usual, while the jaw H is in the inoperative position shown in Fig. 1. When the line has reached the length demanding hand justification, the jaw H is turned to the position shown in Fig. 2, with its operative end between the star-wheel and the matrix line, and the necessary spaces or matrices introduced into the line. When the line is lifted, the parts resume their original positions preparatory to the composition of the next line.

Passing now to the construction shown in Figs. 4, 5 and 6: the assembler-slide F and its finger, and the devices for delivering matrices to the main-assembler, are all constructed as in the preceding figures. In place, however, of the pivoted jaw H , I employ a vertically movable jaw H' , having its lower end weighted and slotted to receive the sustaining stud g' , carried by an arm on the under side of the slide F . The upper end of the jaw H' stands normally below the matrix line and below the star-wheel, as shown in Fig. 4, but after the mechanical assemblage of the line is completed, the jaw H' may be thrust between the star-wheel and the line to confine the right end of the latter, as shown in Fig. 5. Before this finger can be thus lifted, space must be afforded between the matrix line and the star-wheel. In order to provide for this, and at the same time to prevent the accidental oversetting of the line, the slide F is provided with a stop-shoulder f^2 arranged to engage normally a stop-dog f^3 pivoted to the main-frame, in order to encounter the shoulder f^2 and limit the movement of the slide F and its finger f to the left.

When the line has been composed, to a point requiring hand justification, the latch f^3 is turned over to the left out of action and away from the shoulder f^2 , as shown in Fig. 5, thus unlocking the slide F and permitting it to move with the matrix line far enough to permit the jaw H' to rise to its operative position past a confining-stud f^4 on the slide. When the jaw H is thus lifted, it is held firmly in position so that the line between it and the finger f can only be expanded by hand justification to the predetermined length. When the jaw H' is raised to its operative position, it is sustained by a spring f^5 attached to the frame and arranged to engage beneath the lower end of the jaw, as shown in Figs. 5 and 6. When the assembler-slide F is returned to the right to its normal position, after the line has been lifted,

ed, the lower end of the jaw H' is carried clear of the retaining-spring f' and permitted to fall to its original inoperative position.

5 It will be observed that the parts shown in Figs. 4 to 6 have, broadly speaking, the same mode of action as those in the preceding figures, and that the two are mechanical equivalents. In each case the composition 10 of the line is mechanically effected as usual, between the star-wheel E and the finger f , and in each case a supporting dog or abutment is interposed between the star-wheel and the right end of the line, and the distance 15 between this abutment and the finger f positively and accurately limited so that the line may be hand-spaced to the exact length required.

It will be evident to the skilled mechanic 20 that the parts may be widely varied both as to form and arrangement without passing beyond the limits of my invention, the only requirement being that they shall be capable of being thrown into action at will to positively determine the length of the line.

Having thus described my invention, I claim and desire to secure by Letters Patent,

1. In a line-casting machine, the assembling-elevator and the assembler-slide provided with a finger to resist the forward end of the matrix line, in combination with means to limit the advance of the resisting finger, and a movable device adapted to 35 firmly support the rear end of the matrix line at a predetermined distance from the yielding finger; whereby the operator is enabled to justify the lines by hand to a predetermined length.

40 2. In a line-casting machine, the assembling-elevator, the assembler-slide provided with a finger f to support the front of the line, means to definitely limit the advance of the assembler-slide, and a device mounted 45 on a fixed support and movable at will into position to confine the rear end of the matrix line at a predetermined distance from the finger.

3. In a line-casting machine, in combination 50 with means for assembling the matrices in line, means to confine the line at the forward end, and means movable at will into the path of the incoming matrices at a fixed distance from the front confining means, and 55 adapted to rigidly support the rear end of the line; whereby the expansion of the line

is positively limited and the operator enabled to accurately justify the same by hand.

4. In combination with the assembling-slide F having a resistant for the forward 60 end of the matrix line, the star-wheel E , means for delivering matrices between the star-wheel and the resistant, and a pivoted jaw H adapted to be moved to and from the rear end of the matrix line and to give the 65 same rigid support.

5. In combination with the assembler-slide having a finger f , the star-wheel E , the matrix-delivery belt C , the matrix-guiding surface D , and the pivoted jaw H adapted 70 when in one position to form a continuation of the surface D , and when in another position to confine the rear end of the matrix line.

6. In a line-casting machine, the combination 75 of means for assembling the matrices in line, a yielding resistant for the forward end of the line, a jaw adapted to be thrown into position at will to confine the rear end of the line, and a rigid connection between 80 said resisting finger and jaw.

7. In combination with means for assembling matrices in line, a slide F provided with a resistant f , a jaw movable at will to 85 confine the rear end of the line, and means for automatically moving the jaw out of its active position when the slide F returns to its normal position.

8. In a line-casting machine, the combination 90 of a yielding slide F with the resisting finger f thereon, the pivoted jaw H acting to confine the rear end of the line, means for locking the jaw in operative position, and means for automatically releasing the jaw 95 when the slide F is returned to its normal position.

9. In a line casting machine, mechanism 100 for assembling the matrices in line, in combination with supplemental means adapted to embrace the line in the position in which it is composed, and definitely limit its length; whereby the operator is enabled to effect accurate hand justification of the line subsequent to the mechanical composition.

In testimony whereof I hereunto set my 105 hand this twenty eighth day of February, 1908, in the presence of two attesting witnesses.

JOHN R. ROGERS.
